Specification for Design.

Patented Aug. 12, 1913.

Application filed May 5, 1913. Serial No. 765,687. Term of patent 14 years.

To all whom it may concern:

Be it known that I, GEORGE A. KNAAK, a citizen of the United States, residing at Milwaukee, in the county of Milwaukee and State of Wisconsin, have invented a new, original, and ornamental Design for Beer-Pump Casings, of which the following is a specification, reference being had to the accompanying drawing, forming part thereof.

The drawing represents a perspective view of a beer pump casing showing my new design.

I claim:

The ornamental design for a beer pump casing as shown.

In testimony that I claim the foregoing I have hereunto set my hand at Milwaukee in the county of Milwaukee and State of Wisconsin in the presence of two witnesses.

GEORGE A. KNAAK.

Witnesses:

CLEO W. YOUNG,
M. E. DOWNEY.
